UNITED STATES PATENT OFFICE.

JAMES M. STIVEN, OF NEW YORK, N. Y., ASSIGNOR TO HIMSELF, MICHAEL TUOMEY, AND JOHN ELDER, JR., OF SAME PLACE.

IMPROVEMENT IN FIRE-REGULATORS FOR STEAM-BOILERS.

Specification forming part of Letters Patent No. 36,128, dated August 5, 1862.

To all whom it may concern:

Be it known that I, JAMES M. STIVEN, of the city and State of New York, have invented, made, and applied to use a certain new and useful Improvement in Regulators for Steam-Boilers and Steam-Heating or other Apparatus; and I do hereby declare that the following is a full, clear, and exact description of the said invention, reference being had to the annexed drawings, making part of this specification, wherein—

Figure 1 is an elevation of my regulator. Fig. 2 is a side view of the same, and Figs. 3 and 4 are vertical sections at right angles to each other of the said apparatus.

Similar marks of reference denote the same parts.

Various devices have heretofore been made for regulating the admission of air or the escape of the draft from the fire by means of the pressure in the boiler. In these instances the pressure of the steam itself has been employed, and but little motion could be obtained, except by an extent of leverage.

The nature of my invention consists in a cylinder and piston acted upon by water, (that is under pressure transmitted from the boiler through a pipe communicating with the lower portion of the water-space of the boiler,) said piston being provided with a rod and adjusting-screw to regulate the action of a spring and cause the apparatus to be operative by means of different degrees of pressure in the boiler, and the motion thus obtained and regulated is applied through the medium of a lever and suitable connections to open or close the fire-door, the ash-door, the flue-damper, or the cold-air damper; or my said apparatus may be made to act on two or more of these simultaneously, thus causing the pressure in the boiler to become an automatic regulator of the heat through the inlets to or outlets from the furnace, or both.

In the drawings, *a* is a pipe communicating with the water-space of the boiler as low down as convenient. *b* is a water-chamber communicating by the pipe *c* with the cylinder *d*, that is provided with the cover *e*, and contains the piston *f*, that is fitted with the double-cup leathers *1 1*, as shown in Figs. 3 and 4. The piston-rod *g* passes up through the head *e*, and

the upper end is guided in the cylinder *p* at the upper end of the frame *h*. This cylinder *p* is made with a screw-thread on the exterior, taking the cap *m* on the said frame *h*, and *q* is a hand-wheel by which the screw-cylinder *p* can be turned. *l* is a spring around the rod *g*, resting at the lower end on a shoulder, and *o* is an index-pointer extending from the under side of *p* through a slot in *m* to the index *n*. It will now be evident that the pressure of steam in the boiler, acting through the water thereof on the water or other fluid in the chamber *b* and cylinder *d*, will press upon and move the piston *f* and rod *g*, and according to the point at which the spring *l* is compressed by the action of the screw *p* and indicated on the dial *n* by the pointer *o*, so the piston will commence to move with greater or less pressure. Thus in a boiler or in steam-heating apparatus the regulation will be effected after a certain point of pressure and consequent temperature are attained.

In order to communicate the motion from the rod *g*, I employ the lever *k* on a fulcrum at 5, and passing through a mortise in *g*, wherein is a link, *i*, attached by the pin 2, and united with the lever *k* by the pin 3, so that the lever is free to move as the piston-rod goes up or down. From the end or ends of this lever *k* rods or chains pass to the respective doors or dampers, as at 4 and 5. The mode of communicating motion to the doors or dampers through the agency of rods, bent levers, or similar devices will readily suggest themselves to the mechanic according to the circumstances and mode of setting of the furnace or steam apparatus, the operations being so arranged for that the fire is deadened by the checking of the draft as the piston *f* rises, and caused to burn with increased brightness as the piston descends by said doors or dampers directing more draft through the fire.

By the use of the chamber *b* the water in the cylinder *d* is kept cool, and hence not liable to injure the cup-leather packings *1 1*; but a siphon-pipe may be substituted for this chamber *b* and effect the same object.

What I claim, and desire to secure by Letters Patent, is—

1. The cylinder *d*, piston *f*, and chamber *b*, or its equivalent, in combination with the le-

ver *k* and a communication to the dampers or doors employed in steam apparatus for regulating the draft of air according to the pressure of water in the cylinder *d*, as set forth.

2. The screw *p*, spring *l*, and index, in combination with the cylinder *d*, piston *f*, rod *g*, and lever *k*, for the purposes and as set forth.

In witness whereof I have hereunto set my signature this 21st day of June, 1862.

JAMES M. STIVEN.
